UNITED STATES PATENT OFFICE.

HARRY C. THOMPSON, OF SCHENECTADY, NEW YORK, ASSIGNOR TO GENERAL ELECTRIC COMPANY, A CORPORATION OF NEW YORK.

AMPLIFYING SYSTEM.

Application filed February 26, 1921. Serial No. 447,971.

To all whom it may concern:

Be it known that I, HARRY C. THOMPSON, a citizen of the United States, residing at Schenectady, county of Schenectady, State of New York, have invented certain new and useful Improvements in Amplifying Systems, of which the following is a specification.

My present invention relates to amplifying systems, and more particularly to systems employing electron discharge devices of the dynatron or negative resistance type.

In the operation of such devices in the past it has been customary to supply the electrical variations to be amplified directly to the negative resistance circuit and thereby vary the potential of the secondary cathode with respect to the primary cathode, at the same time maintaining the anode potential constant. The amplifying action takes place entirely in the negative resistance circuit and the amplified variations are either utilized in this circuit or supplied either by direct or inductive coupling to other circuits. One of the disadvantages arising from this method of operation lies in the fact that in order to utilize this circuit as both the input and output circuit, some inductance must be included in the circuit and under these circumstances the circuit has an inherent tendency to oscillate by reason of its negative resistance characteristic.

The object of my present invention is to provide a circuit arrangement which will make use of the negative resistance characteristic of such devices for amplification, and in which the input and output circuits will be entirely stable in their operation.

The novel features which I believe to be characteristic of my invention are set forth with particularity in the appended claims, my invention itself, however, both as to its organization and method of operation, together with further objects and advantages thereof will best be understood by reference to the following description taken in connection with the accompanying drawing in which Figs. 1 and 2 illustrate diagrammatically two different circuit arrangements which may be employed in carrying my invention into effect.

As indicated in Fig. 1, I employ an electron discharge device 1, having the usual filamentary cathode 2 adapted to be heated to incandescence by means of current de-

rived from the source 3, a grid electrode 4 and a third plate electrode 5 surrounding the cathode and grid electrode. A battery 6 or other convenient source of direct current may be employed for impressing a positive potential upon the grid electrode 4 and a second source 7 for impressing a positive potential upon the plate electrode 5 with respect to the cathode 2. The potential of the plate electrode 5 in this instance is higher than that of the grid electrode 4 and these potentials are so chosen that the plate electrode 5 acts as anode and the grid electrode 4 acts as secondary cathode.

In the usual operation of such devices in the past the variations to be amplified have been impressed upon a circuit between the primary cathode and the secondary cathode so as to vary the potential of the secondary cathode with respect to the primary cathode, the potential of the anode remaining constant with respect to the primary cathode. This arrangement has the disadvantages mentioned above and to overcome this disadvantage I impress the variations to be amplified upon the system in such a way that the potential of the primary cathode is varied with respect to both the secondary cathode and the anode. This is accomplished by impressing the electrical variations to be amplified upon the system by means of the transformer 8, the secondary of which is common to the circuit between primary cathode and anode and the circuit between primary cathode and secondary cathode.

Assuming that the potentials of the two electrodes 4 and 5 are fixed by means of the batteries 6 and 7, the potential of the primary cathode 2 with respect to electrodes 4 and 5 will vary in accordance with potential variations produced in the secondary of transformer 8. This will produce variations in the current to electrode 4 by reason of the negative resistance characteristic of the system and equal and opposite variations in the current to electrode 5. The current in the circuit between cathode 2 and batteries 6 and 7 in which the secondary of transformer 8 is included will therefore be entirely independent of the negative resistance characteristic of electrode 4 and will be either constant and independent of potential variations of transformer 8 in case the filament temperature is low, or will have a positive

105

110

resistance characteristic varying as the three halves power of the potential variations of transformer 8 if the filament temperature is high. The variations of the potential of the 5 primary cathode with respect to anode 5 produced in the secondary of transformer 8 will have substantially no effect upon the negative resistance characteristic if the potential of anode 5 is made high enough with 10 respect to the electrode 4. The operating characteristics of the device are therefore unaffected by the change in connections which I have described.

The negative resistance of the device may 15 be balanced by means of a positive resistance 9 so that small variations in the potential of the primary cathode with respect to the secondary cathode will produce large variations in current flowing between primary cathode and secondary cathode. In 20 order to eliminate the necessity of inserting any inductive device in any portion of the circuit which has a negative resistance characteristic, potential variations set up across 25 resistance 9 may be impressed upon the grid circuit of an electron discharge amplifier 10 and the telephone receiver 11 in the plate circuit of this amplifier will give an indication of the amplified variations if these happen to be of audible frequency. If the variations to be amplified are of radio frequency 30 then the device 10 may also act as a detector. If desired, a variable condenser 12 may be inserted in shunt to the secondary of transformer 8 for tuning the input to the variations which are to be amplified.

In Fig. 2 I have shown a circuit arrangement which is similar in its manner of operation to that shown in Fig. 1, the main 40 difference however being that the function of the electrodes 4 and 5 is interchanged. In this case the electrode 5 acts as a secondary cathode and the electrode 4 as the anode. Since the current variations in the negative resistance circuit produce corresponding equal and opposite variations in the circuit flowing in the anode circuit, the telephone receiver 11 may be inserted in the anode circuit as indicated.

50 While I have shown and described the preferred embodiments of my invention, it will be understood that my invention is by no means limited to the particular circuit arrangements shown as many variations in the electrical connections employed as well as in the form of apparatus used may be made without departing from the scope of my invention as set forth in the appended claims.

60 What I claim as new and desire to secure by Letters Patent of the United States, is,—

1. An amplifying system comprising an electron discharge device having an electron emitting cathode, an anode and a third electrode enclosed in an evacuated receptacle,

sources of potential applied to said electrodes in such a way that the device has a working range over which the current flow from the cathode to the third electrode varies inversely as the potential applied thereto 70 and means for varying the potential of the cathode with respect to both the anode and third electrode in accordance with the electrical variations which are to be amplified.

2. An amplifying system comprising an 75 electron discharge device having an electron emitting cathode, an anode and a third electrode enclosed in an evacuated receptacle, sources of potential applied to said electrodes in such a way that the device has 80 a working range over which the current flow from the cathode to the third electrode varies inversely as the potential applied thereto, a circuit between cathode and anode, a circuit between cathode and third electrode 85 and means common to both of said circuits for supplying to the system electrical variations which are to be amplified.

3. An amplifying system comprising an 90 electron discharge device having an electron emitting cathode, an anode and a third electrode which is interposed between cathode and anode, sources of potential applied to said electrodes in such a way that the device has a working range over which the current 95 flow from the cathode to the third electrode varies inversely as the potential applied thereto and means for varying the potential of the cathode with respect to both the anode and third electrode 100 in accordance with the electrical variations which are to be amplified.

4. An amplifying system comprising an 105 electron discharge device having an electron emitting cathode, an anode and a third electrode which is interposed between cathode and anode, sources of potential applied to said electrodes in such a way that the device has a working range over which the current 110 flow from the cathode to the third electrode varies inversely as the potential applied thereto, a circuit between cathode and anode, a circuit between cathode and third electrode, and means common to both of said circuits for supplying to the system electrical variations which are to be amplified.

5. An amplifying system comprising an 115 electron discharge device having an electron emitting cathode, an anode and a third electrode, circuit connections between the 120 different electrodes, sources of potential included in said circuit connections of such values that the current flow in a portion of said circuit connections over a predetermined range of applied potential varies inversely as the applied potential, and means 125 for impressing potential variations upon a portion of the circuit connections in which the current flow is independent of the applied potential.

6. An amplifying system comprising an electron discharge device having an electron emitting cathode, an anode and a third electrode, circuit connections between the different electrodes, sources of potential included in said circuit connections in such a way that in a portion of the circuit connections the current flow over a predetermined range of applied potential varies inversely as the applied potential, and means for impressing potential variations upon another portion of the circuit connections and thereby varying the potential relations between the electrodes.
7. An amplifying system comprising an electron discharge device having an electron emitting cathode, an anode and a third electrode, circuit connections between the different electrodes, sources of potential included in said circuit connections in such a way that in a portion of the circuit connections the current flow over a predetermined range of applied potential varies inversely as the applied potential and means for impressing potential variations upon another portion of the circuit connections and thereby varying the potential relations between the electrodes.
